UNITED STATES PATENT OFFICE.

ABRAM A. KNOWLES, OF CANYON FERRY, MONTANA.

SLEIGH RUNNER.

Application filed October 14, 1922. Serial No. 594,448.

To all whom it may concern:

Be it known that I, ABRAM A. KNOWLES, residing at Canyon Ferry, in the county of Lewis and Clarke and State of Montana, a 5 citizen of the United States, have invented certain new and useful Improvements in Sleigh Runners; and I do hereby declare the following to be a full, clear, and exact description of the invention, such as will enable others skilled in the art to which it pertains to make and use the same.

My invention relates to improvements in sleigh runners, and more particularly to runners for use on motor sleighs.

15 The object of the invention is to provide the runners with means for preventing the skidding or lateral sliding of the same which has in the past been responsible for many accidents which have caused injuries and sometimes deaths.

20 A further object is to provide the runners of a sleigh with means for preventing skidding which is simple, inexpensive, and durable in construction, easy to apply, and does not change the general design or shape of the runners.

25 The invention consists in the several features and in the construction, combination of such features as more fully hereinafter described and claimed.

30 Referring to the drawings:—

Fig. 1 is a side elevation of a runner made in accordance with my invention.

35 Fig. 2 is a cross section on the line 2—2 of Figure 1 on an enlarged scale.

Fig. 3 is a similar view to Figure 2 with the parts separated or disassembled.

Fig. 4 is a section on the line 4—4 of Figure 3.

40 In the drawings in which similar reference characters denote similar parts throughout the several views, 1 represents a runner, constructed in accordance with my invention, provided with a central vertical part 2, two 45 similar shaped lateral parts 3 each provided with an upwardly extending vertical flange 4 on its inner edge, a horizontal substantially

flat flange 5 at its outer edge and a downwardly and inwardly curved part extending from the inner portion of the flange 5 to the 50 lower portion of the flange 2.

Each of the flanges 4, and the central vertical part 2 have a slot and a series of bolt holes 6 respectively to receive bolts 7 to provide means for vertically adjusting the part 55 2 with relation to the parts 3 when it is desired to have the part 2 depend, more or less, below or beyond the under surface of the parts 3.

The part 2 extends, preferably, from the 60 point 8 to point 9 as that portion of the runner is generally in direct contact with the snow or ice between those points, but if found desirable the part 2 could be made longer.

65 The several parts of the runner are made of pressed steel but any other material may be used.

I do not wish to be understood as limiting myself to the specific details of construction 70 and arrangement as herein described and illustrated, as it is manifest that variations and modifications may be made in the features of construction and arrangement, in the adaptation of the device to various conditions of use, without departing from the spirit and scope of my invention and improvements. I therefore reserve the right to all such variations and modifications as properly fall within the scope of my invention and the terms of the following claim.

75 What I claim is:—

A sleigh runner consisting of separate lateral parts each having an upwardly extending flange, a wide upwardly curved portion terminating in a horizontal portion and a vertical part located between said upwardly extending flanges and secured thereto, in such manner that they may be adjusted vertically with relation thereto, and projecting below 85 90 said lateral parts.

In testimony whereof I have affixed my signature.

ABRAM A. KNOWLES.
